C. G. PULLIN

METHOD AND MEANS FOR CONTROLLING INTERNAL COMBUSTION ENGINES

Filed July 20, 1920

UNITED STATES PATENT OFFICE.

CYRIL GEORGE PULLIN, OF ISLEWORTH, ENGLAND.

METHOD AND MEANS FOR CONTROLLING INTERNAL-COMBUSTION ENGINES.

Application filed July 20, 1920. Serial No. 397,563.

To all whom it may concern:

Be it known that I, CYRIL GEORGE PULLIN, a subject of the King of Great Britain, residing at Isleworth, Middlesex, England, have invented an Improved Method and Means for Controlling Internal-Combustion Engines, of which the following is a specification.

This invention relates to an improved method of controlling internal combustion engines, and has for its object to provide means whereby only predetermined volumes of the combustible mixture are subjected to full compression.

15 Generally speaking, the admission of a combustible mixture to the cylinder is controlled by levers regulating the flow through the fuel orifice from the carburetter or from the mixing chamber of the carburetter.

20 According to this invention, the control is effected by releasing or exhausting a portion of the combustible mixture admitted to the combustion chamber during the compression stroke so that only a portion of 25 total charge is subjected to full compression, thereby regulating the output of the engine.

The invention consists in a method of controlling an internal combustion engine 30 in which a portion of the charge admitted through the combustion space is returned to the source of supply, before ignition takes place in the cylinder, the amount returned determining the compression in the combustion space, and in the means of effecting the removal of a predetermined portion of the charge to the combustion space.

Broadly speaking, the means consists of a spring controlled valve with a wire drawing 40 passage and means for adjusting the tension of the spring whereby the said wire drawing tends to raise internal pressure, so as to close the said valve against the action of the said spring when the predetermined pressure regulable by the spring, is reached.

In order that my invention may be clearly understood, I will now describe the same with reference to the accompanying drawings, in which, Fig. 1 shows in central vertical section, an internal combustion engine, fitted with a control means, constructed according to this invention, and Fig. 2 is an elevation of the control means partly in 55 section and to an enlarged scale.

The engine illustrated from the drawings, is of a two-cycle type and the cylinder and crank case, as shown, are cast in one, and in the cylinder wall, a transmission passage is formed, running along its length and connecting the crank chamber by ports running through the inner end of the cylinder, the crank case having formed in one side an induction passage, being a continuation of the said transmission passage running lengthways of the cylinder, and so formed as to be connected to the supply of mixture from the carburetter.

The crank case is preferably formed with a detachable side plate and the cylinder with a detachable head so that the piston and its connecting rod can be inserted through the open end of the cylinder and placed in position on the crank shaft with ease.

For a clear understanding of the invention, the engine shown in Fig. 1 will first be described, and then its operation, and afterwards the effect of the control valve on such operation will be referred to.

Referring first to Fig. 1, the engine piston 1 works in the cylinder 2, cast in one with a closed crank case 3 of an internal combustion engine, the piston having a perforated skirt 4 and a deflector head 5 with transverse cruciform webs 6, internally arranged, the piston being driven from a crank disc 7 to which it is connected by a gudgeon pin 8 and a connecting rod 9. The gudgeon pin 8 is of a hollow type and particularly connected to its connecting rod, so as to provide a clearance between the connecting rod and the bearings of the gudgeon pin. By this means the piston and its connecting rod can be inserted in the cylinder before the detachable head 10 is secured in position, and, due to the clearance just referred to, the connecting rod can be slightly tilted until it is in position to pass on to the crank pin of the crank disc 7. The cylinder is formed as before stated, with a transmission passage 11 provided in the wall of the cylinder and which is connected to both ends of the combustion space at the lower pressure end by an inlet port 12 and at the high pressure end by an outlet port 13. The crank case 3 is formed within its wall with an induction passage 14 communicating with the transmission passage 11 and leading from an induction valve 15 to the crank chamber via a port 16. The exhaust open-

ings 17 are formed substantially opposite the inlet ports 12 in the cylinder 2.

The numeral 35 indicates the silencer for the engine.

5. The cycle of operations, when the engine is running on full charge, is as follows:—

The piston 1 makes an outstroke, and due to the reduction of pressure and to an ultimate negative pressure in the crank case 3,

10 mixture is sucked in through the induction passage 14 formed in the wall of the crank case 3, through the port 16 at the crank case end of the cylinder, and then through the skirt 4 of the piston, or behind the piston

15 to the crank case. The piston then makes an instroke, compressing the charge in the crank case and driving it out through or behind the piston, through the port 16 to the

20 transmission passage 11 formed longitudinally of the cylinder, and through the cylinder inlet ports 12 on the firing side of the piston, to the combustion space. The piston then again advances on an outstroke, compressing the mixture in the combustion

25 space of the cylinder, closing the inlet ports 12 to the cylinder and the exhaust ports 17 from the cylinder, while at the same time inducing a fresh charge to the crank case.

At the commencement of the next instroke, 30 the ignition of the gases is effected and the working stroke commences, again compressing the charge in the crank case, then driving it out through the said port 16 in the crank case end of the cylinder wall, up

35 through the transmission passage, and through the inlet ports 12 to the combustion space, the new charge being so directed in its entry by the deflector head 5 of the piston to the combustion space of the cylinder,

40 that it drives out the burnt gases through the exhaust ports 17 which have been simultaneously uncovered with the inlet ports 12 as the piston completed its instroke. The

45 scavenging have been effected by the new charge, a new cycle of operations commences.

Now when the speed of the engine is required to be modified, a portion of the charge admitted to the combustion space is

50 permitted to escape through the outlet 13 and back down the transmission passage 11 to the source of supply; in this case the closed crank chamber 3.

This control valve, is so constructed as

55 to automatically close, when a predetermined pressure in the combustion space is obtained, that is, when the predetermined portion of the charge to be removed has

60 passed through the outlet 13.

The preferred construction of this control valve will be afterwards described, with particular reference to Fig. 2.

The induction valve 15 is of the type influenced by the negative pressures in the

65 crank chamber obtained on the successive

upstrokes of the piston and in the construction shown, the valve is of that type, which, when operated to admit fuel to the mixing chamber 37 for supply to the crank case, also permits a flow of lubricant through a 70 suitable conductor, such as 38, to the distributing port 39, substantially midway of the engine cylinder, so that the piston is always automatically supplied with oil, while the engine is working. 75

It will be obvious with such a construction, the valve 15 will lift according to the negative pressures in the crank case, and the negative pressures will vary according to the amount of gases removed from the combustion space, and return to the crank case. 80

The reference numeral 20 designates a silencer for the exhaust gases.

The control valve 18 is provided with an extended spindle 19 and the seating for the valve is formed by a guide member 20 provided with circumferential openings 21 communicating with the interior of the guide member. The head of the valve 18 is further provided with depending flanges 22 riding within the guide member and having ports 23 formed therein, and adjacent the head of the said valve. 85

It will be seen by this construction, that the member 20 guides the valve 18 by providing a path of movement for the spindle 19 and for the depending flange 22. The guide member 20 also forms on its inner extremity 24 the seating for the valve, the guide member 20 being retained in position by a casing 25, hereinafter referred to as the valve casing, which is retained in position in the wall of the cylinder by an externally gland member 26 engaging internal threads formed within the extension of the outer wall adjacent the outlet 13. By screwing down the gland 26, the casing 25 presses the guide 20 against the inner face 27 of the transmission passage 11. The valve spindle 19 has a threaded extremity 28, on which is fixed a nut member 29 and the compression spring 30 is disposed between the end of the casing 25 and the said nut member 29. A sleeve member 31 which is slidably disposed on the spindle 19, limits the movement of the valve spindle impressed by the spring 30 on the nut 29, by reason of its abutting against the said nut, and by the provision of a projection 32 preferably in the form of a handle projecting from the said sleeve member through a slot 33 formed in the wall of the casing, the pitch of the slot being sufficiently small to prevent the spring member effecting a sliding movement of the projections 32 within the said slot. 100

It will be noted that the spring 30 always tends to lift the valve, but it is limited in its effect by the engagement of the sleeve member 31, which is slidable within the 105

110

valve casing, with the nut member 29 on the valve spindle.

In the initial position, that is, when the full charge in the engine cylinder is to be subjected to compression and ignition, the sleeve 31 is in its outermost position relative to the cylinder and by engagement with the nut 29 on the valve spindle as aforesaid, retains the valve on its seating formed in the wall of the cylinder.

When the predetermined portion of the mixture is desired to be liberated from the compression space the sleeve member 31 is given a longitudinal displacement within the valve casing 25 by operation of the control member 32. In this position the valve 18 is maintained off its seating by the pressure of the spring 30, and the opening space between the valve and its seating is regulated by the amount of longitudinal displacement of the sleeve member 31 which as aforesaid, directly regulates the effective effort of the spring. In this position of the valve from its seating, a portion of the mixture commences to flow from the combustion chamber as the engine piston commences its compression stroke, the expelled gases flowing out between the valve 18 and its seating, through the ports 23, in the depending flanges 22, then outwards through the internal space, within the guide 20 and out through the circumferential openings 21 to the transmission passage 11. The flow of the gases between the valve and its seating obtain an accelerated velocity as the piston advances until the desired wire-drawing effect is produced, for as the mixture is unable now to quickly leave the cylinder, the pressure therein immediately rises and overcomes the effective effort of the spring member, whereon the valve closes on its seating and thereafter the usual cycle of the engine follows.

It will be seen then that according to the position of the sleeve within the valve casing the opening between the valve and its seating will vary, and accordingly the wire-drawing effect will take place at different positions of the piston in its compression stroke, and that as the desired position of the stroke is obtained the compression in the cylinder overcomes the effect of the spring at that position and compression of the desired proportion of the total charge in the cylinders is effected and subsequently ignited in the usual way.

Graduations 34 may be formed along the slot or in any suitable way, either to show the tensional effort of the spring in each position, or to show the position of the piston in the working cylinder when the choking or wire-drawing effect obtains the closing of the combustion space.

I claim:—

1. Means for controlling an internal com-

bustion engine, comprising a spring-controlled valve member having a wire-drawing passage, and means for adjusting the tension of the spring, whereby the said wire-drawing tends to raise the internal pressure so as to close the said valve against the action of the said spring when a predetermined pressure, regulable by the spring, is reached.

2. In an internal combustion engine, means for regulating the compression in the combustion space, by controlling the exit therefrom of a portion of the charge, comprising a valve, a seating therefor at the high pressure end of said combustion space, wire-drawing passages between said valve and seating, a spring tending to keep said valve from said seating, and means for adjusting the lift of the valve effected by said spring, whereby the said wire-drawing tends to raise the internal pressure so as to close the said valve against the action of the said spring when a predetermined pressure, regulable by the spring, is reached.

3. Means for regulating the compression in the combustion space in an internal combustion engine, having in combination a working cylinder having an exit at the high pressure end of the combustion space, a valve seating in said exit, a valve, a valve spindle, said valve having wire-drawing openings in the head thereof, an enlargement at that extremity of the spindle away from the head, a guide for said spindle, a casing for said valve spindle, means securing said casing to said engine cylinder, a spring within said casing pressing against said enlargement on the valve spindle and tending to lift the valve from its seating, means engaging the other side of said enlargement for limiting the lifting movement of said valve, and means operable from outside said casing for adjusting the position of said valve lift limiting means.

4. Means for regulating the compression in the combustion space of an internal combustion engine having in combination, a working cylinder having a longitudinal transmission passage in the wall thereof and an exit from the combustion space at the high pressure end thereof, said transmission passage communicating with the said exit, a valve seating in said exit, a valve, a valve spindle, said valve having wire-drawing openings in the head thereof, an enlargement at that extremity of the spindle away from the head, a guide for said spindle, a casing for said valve spindle, means securing said casing to said engine cylinder, a spring within said casing pressing against said enlargement on the valve spindle and tending to lift the valve from its seating, means engaging the other side of said enlargement for limiting the lifting movement of said valve, and means operable from outside said cas-

ing for adjusting the position of said valve lift limiting means.

5. Means for regulating the compression in the combustion space in an internal combustion engine, having in combination a working cylinder having an exit at the high pressure end of the combustion space, a valve seating in said exit, a valve, a valve spindle, said valve having wire-drawing 10 openings in the head thereof, an enlargement removably attached at that extremity of the spindle away from the head, a guide for said spindle, a casing for said valve spindle having a cam slot in the wall thereof, 15 means securing said casing to said engine cylinder, a spring within said casing pressing against said enlargement on the valve spindle and tending to lift the valve from its seating, a hollow piston member slidable 20 within said casing and having a central aperture for the projection therethrough of the valve spindle and normally abutting against said enlargement, a projection fixed to said hollow piston member and protruding 25 through said cam slot in casing, and means for moving said projection in cam slot whereby the lift of said valve may be regulated.

6. Means for regulating the compression 30 in the combustion space of an internal combustion engine having in combination, a working cylinder having a longitudinal transmission passage in the wall thereof and an exit from the combustion space at the 35 high pressure end thereof, said transmission passage communicating with the said exit, a valve seating in said exit, a valve, a valve spindle, said valve having wire-drawing openings in the head thereof, an enlargement 40 removably attached at that extremity of the spindle away from the head, a guide for said spindle, a casing for said valve spindle having a cam slot in the wall thereof, means securing said casing to said engine 45 cylinder, a spring within said casing pressing against said enlargement on the valve spindle and tending to lift the valve from its seating, a hollow piston member slidable within said casing and having a central aperture 50 for the projection therethrough of the valve spindle and normally abutting against

said enlargement, a projection fixed to said hollow piston member and protruding through said cam slot in casing, and means for moving said projection in said cam slot, 55 whereby the lift of said valve may be regulated.

7. In a two-stroke internal combustion engine, a mixture supply valve operable by the negative pressures in said crank chamber, an induction passage leading from said valve to said crank chamber, means for compressing the admitted volume by a stroke of the piston, a transmission passage for the compressed gases communicating with said induction passage, and connecting the crank chamber with both ends of the combustion space, means for automatically effecting a wire drawn ejection of a portion of the gases from the combustion chamber to the transmission passage, whereby the removed gases may be returned to a source of supply of gas on a subsequent cycle, supply means for effecting the removal of a portion of the gases from the engine cylinder, comprising in combination with the said cylinder, a valve disposed to control the communication between the higher pressure end of the combustion space and the said transmission passage, a valve seating in said communication, 80 an extended spindle for said valve, wire drawing openings in the head of said valve, an enlargement removably attached at that extremity of the spindle of the spindle away from the head, a guide for said spindle, a casing for said valve spindle having a cam slot in the wall thereof, means securing said casing to said engine cylinder, a spring within said casing pressing against said enlargement on the valve spindle and tending to lift 85 the valve from its seating, a hollow piston member slidable within said casing and having a central aperture for the projection therethrough of the valve spindle and normally abutting against said enlargement, a projection fixed to said hollow piston member and protruding through said cam slot in casing, and means for moving said projection in cam slot whereby the lift of said valve may be regulated. 90

In testimony whereof I affix my signature.
CYRIL GEORGE PULLIN.
